(57) **CLAIM**

The ornamental design for a pet carrier vent panel, as shown and described.

DESCRIPTION

FIG. 1 is a perspective view of the pet carrier vent panel of the present design.

FIG. 2 is a partial enlarged perspective view of a portion of FIG. 1.

FIG. 3 is a front elevation view of the pet carrier vent panel of the present design; and,

FIG. 4 is a partial enlarged front elevation view of a portion of FIG. 3.

The broken lines showing the pet carrier in FIG. 1 depict environmental subject matter, are for illustration only and form no part of the claimed design.

The dot-dot-dash line in FIGS. 2, 3 and 4 around the periphery of the pet carrier vent panel defines the boundary between the claimed and non-claimed subject matter.

The dotted lines encircling the portion of the pet carrier vent panel and the arrows in FIGS. 1 and 3 are for the purpose of identifying the partial portions of the pet carrier vent panel which are shown in the enlarged views of FIGS. 2 and 4, respectively, and form no part of the claimed design.

The circles within the pet carrier vent panel are apertures.
